UNITED STATES PATENT OFFICE

FRANZ LANG, OF BUCYRUS, OHIO, ASSIGNOR TO W. A. RIDDELL COMPANY, OF BUCYRUS,
OHIO, A CORPORATION OF OHIO

GRINDER.

Application filed December 27, 1929. Serial No. 416,839.

This invention, relating as indicated to grinders, has specific reference to grinders commonly employed in reducing clay, hard shale, etc., to a suitable fineness preparatory to the manufacture of brick and like products.

Grinders for the above purpose as now constructed are excessively heavy, take up unreasonable amounts of floor space, and are generally constructed in a loosely knit fashion so that the various operating parts are subject to unusual amounts of wear and the machine generally is cumbersome beyond the point where a quiet and efficient operation of the grinding machine is possible. In the construction of such grinders the grinding operation is performed by a plurality of exceptionally heavy mullers which are rotatably supported and rest upon a rotating bed or pan. The material to be ground is fed onto the rotating pan, and in passing under the mullers is crushed to a suitable fineness.

Grinders as now constructed have the shaft by which the revoluble pan is driven and supported, revolubly supported on a step or suitable bearing positioned in the pit below the revoluble pan. The bearing for axially supporting the shaft when so positioned in the pit under the revoluble pan is in direct communication with all of the dirt, dust and ground material which is discharged from the revoluble pan and therefore the life of such bearing is consequently relatively short. It is an object of my invention to provide a grinder in which the revoluble pan is axially supported by a bearing lying above the pan and out of the zone of deteriorating elements.

A further disadvantage in the construction of grinders now commonly employed is that the supporting frame for the grinder consists mainly of wide sprawling legs which materially interfere with free and ready access to the grinding mechanism proper, and which in addition are excessively heavy and expensive to manufacture. It is an object of my invention to provide a supporting frame structure for a grinder which shall be compact, rigid and furnish all the necessary requirements of a good frame structure having the added advantage of low cost of manufac-

ture, as well as ease and simplicity of assembly.

The mullers above referred to, which are revolubly carried by the grinding pan, have, in structures heretofore employed, been directly supported by the revoluble pan and consequently when such mullers pass over the rough material on such pan the entire mechanism is subjected to a considerable amount of unreasonable shock or impact destructive to the entire grinding mechanism. It is an object of my invention to provide a means for supporting such mullers with respect to the revoluble pan that a considerable portion of the destructive shock or impact, due to the operation of such mullers, is entirely obviated.

A further source of considerable inconvenience in the operation of grinders of the type above described is that when the material to be ground is fed onto the revoluble pan the muller which first receives such material is apt to become choked and the entire operation of the grinding machine interfered with. In order that the material to be ground shall be received in equal quantities by the respective mullers on the revoluble pan I have provided a means whereby such even distribution may be effected and the efficiency of the grinding mechanism appreciably increased.

In the grinding of dry or even wet clay, shale, etc., considerable dust is raised during the grinding process, and this dust has in the machines now commonly employed, caused excessive wear on the operating parts of such machine to the end that the life of the various operating parts was relatively short, necessitating frequent and expensive replacement of parts, which also interfered with the continuous operation of the grinder. It is a further object of my invention to provide a structure in which the various operating parts are so shielded from the dust and dirt in the air so as to appreciably add to the quietness of the operation of the machine as well as a lengthening of the life of the various operating parts.

Other objects of my invention will appear as the description proceeds.

To the accomplishment of the foregoing and related ends, said invention, then, consists of the means hereinafter fully described and particularly pointed out in the claims; the annexed drawings and the following description setting forth in detail certain structures embodying the invention, such disclosed means constituting, however, but one of various mechanical forms in which the principle 10 of the invention may be used.

In said annexed drawings:

Fig. 1 is a part sectional plan view of the grinder comprising my invention; Fig. 2 is a half section half elevation of the grinder 15 shown in Fig. 1; and Fig. 3 is a part section part elevation of the grinder taken on a plane substantially at right angles to the view shown in Fig. 2.

Referring more specifically to the drawings, and more especially to Figs. 1 and 3, the grinder here illustrated consists of substantially bell-shaped complementary elements 1 and 2, which consist of reinforced legs 3, 4, 5 and 6 formed integrally therewith, which serve as a main supporting means for the entire structure. It will be noted in this connection that the legs 5 and 6 above referred to are formed of complementary elements, integral with each of the sections 1 and 2. The 20 sections 1 and 2 are removably secured to each other by means of the bolts 7 so that when such sections are so united they present a substantial bell-shaped body, as shown in Figs. 2 and 3. The supporting legs 3, 4, 5 and 6 are suitably cross-braced by means of webs 8 and 9 which are so positioned as not to interfere with the ready access to the interior of the grinding mechanism. The sections 1 and 2 have cross bars 10 and 11 formed integrally 25 therewith at their upper portions, as most clearly shown in Fig. 1, which cross bars, when the sections 1 and 2 are in juxtaposition, provide a support for the hollow member 12 which depends from the supports into the body of the bell-shaped frame. Positioned within, and upon the top of the bell-shaped body, is a dome-shaped member 13, which is removably secured to the body by means of the bolts 14 and has an auxiliary cover 15 removably secured thereto by means of the bolts 16. The dome-shaped cover 13, as most clearly shown in Fig. 2, is adapted at 17 to revolvably support the drive shaft 18 and its associated driving mechanism. The drive shaft 18 is terminally supported by friction reducing bearings 19, which are rigidly mounted in the bearing bracket 20 formed integrally with the dome-shaped member 13 and is, adjacent its opposite end 21, revolvably supported by the frictionless bearings 22 which are mounted in the block 23 carried by the extending arm or bracket 24 formed integral with the bell-shaped body adjacent the supporting leg 3. The shaft 18 has rigidly secured thereto a drive pulley 25 by means of the

key 26. Associated with the shaft 18 intermediately the bearings 19 and 22 is a suitable clutch mechanism 27 which, when actuated by the lever 28, may effect driving connection between the shaft 18 and the driving pinion 29 coaxially mounted thereon. A lubricant duct 30 is provided for introducing a suitable lubricant to the bearing 19.

Positioned within the dome-shaped member 13 is a supporting member 31 which has an annular ring 32 adapted to support the thrust bearing 33, which in turn supports the thrust element 34 and the thrust ring 35. The thrust ring 35 is secured in a circumferential groove 36 in the upper portion 37 of the shaft 38. The shaft 38 has keyed thereto the hub 39 of the bevel driving gear 40 adapted to intermesh with the driving pinion 29 carried by the driving shaft 18. The upper portion of the shaft 38 is laterally 75 revolvably supported by means of the friction reducing bearing 41 which is positioned intermediately the auxiliary cover 15 and the annular member 42. The annular member 42 has a circumferential skirt 43 formed integrally therewith adapted to serve as a dirt-excluding means for the bearing 41 with the projecting ridge 44 formed integrally with the auxiliary dome member 15.

The shaft 38 is coaxially positioned within the aperture 45 formed centrally of the hollow vertically disposed member 12. The shaft 38 has keyed thereto at its lower portion 46 the pan 47 by means of the key 48. The pan 47 is coaxially secured to the shaft 38 by means of the collar 49 seated in the groove 50 formed in the terminal portion of this shaft. The pan 47 has removably secured thereto the wearing plate 51 by means of the securing bolts 52. The shaft 38 is laterally supported immediately above the pan 47 by means of the bushing 53 carried by the removable body 54 secured to the lower end of the hollow member 12. The member 54 has a circumferentially depending skirt 55 formed integrally therewith which, with the member 56, serves as a dust excluding means for protecting the bushing 53 from the dust arising from the revoluble pan 47. The member 56 is secured at its lower end by means of the bolts 57 to the circumferentially extending flange member 58 and the annular member 59, the annular member 59 being removably secured to the pan 47 by means of the bolts 60. The oil-tight cavity 100 formed by the dust excluding members just referred to has an oil sight-gauge 61 secured therein, by means of which the level of the oil in this cavity may be observed through the transparent plate 62.

The lower portion of the dome-receiving recess in the upper region of the grinder frame has an oil trough 63 secured thereto into which depends the spout-shaped extension 64 which, upon rotation of the gear 40, 110

causes the lubricant from the trough 63 to flow by centrifugal force through the conduit 65 onto the face 66 of the gear 40. The lubricant is thence thrown against the side of the dome-shaped aperture and flows back to the trough 63. Some lubricant will find its way down along the side of the shaft 38 through the bushing 53 and into the receptacle therefor formed by the dust-excluding elements above referred to. It will be seen that the entire operating mechanism is therefore at all times running in a bath of oil and is not subject to the erosive action of the dust necessarily incidental to the grinding operation.

The mullers 67, while forming no part of this invention, will be briefly described as formed of a plurality of segments encompassed by a tire 68, which is readily replaceable when worn as a result of the grinding operation. The mullers 67 are revolvably mounted by means of the friction reducing bearings 68 on the shaft 69 which, as most clearly shown in Fig. 1, has crank arms 70 and 71 formed integrally therewith on its terminal portions. The crank arms 70 and 71 are suitably journaled in the bearings 72 and 73, respectively formed therefor in the legs 3 and 4 of the bell-shaped frame and the vertically disposed hollow member 12. The hollow member 12 and the supporting legs referred to have spring-receiving brackets 74 and 75 formed integrally therewith, as most clearly shown in Fig. 2, which secure the springs 76 and 77 carrying the supporting members 78 and 79. These springs and their associated supporting members sustain the arms 70 and 71 sufficiently so that when no material is in the pan the mullers 67 will lightly rest on the plates 51.

Circumferentially disposed above the pan 47 is a ringlike member 80 which is adjustably supported from the member 81 by means of the screws 82 and 83. The member 80 has a wear plate 84 removably secured thereto by means of the bolts 85. The purpose of the member 80 and its associate wear plate 84 is to regulate the fineness of the materials which is discharged from the revoluble pan 47. By positioning the wear plate 84 closer to the surface of the rotating table the material which passes from the rotating table thereunder, due to centrifugal force, can be regulated to the desired fineness.

As most clearly shown in Fig. 1, positioned along the side of the feeding ends of the respective mullers are scraper elements 86 supported by the brackets 87 which are removably and adjustably secured to the side frame of the grinder. These brackets supporting the scrapers, are independently adjustable, the amount of material fed under each of the respective mullers can be accurately regulated to prevent the muller adjacent the feed chute from receiving more than its share of the material to be ground.

It will be apparent from the above described construction that the grinder comprising my invention has as its salient features the axially supported grinding pan supported at a point above the grinding area 70 so that the old form of step or thrust bearing occurring in the pit under the grinder is entirely done away with. Further, that the entire driving mechanism of the grinder proper is entirely enclosed within dirt and dust excluding means so that such mechanism is at all times operating in a bath of oil. The construction of the muller supports furnishes a resilient means whereby the harmful jarring action of the mullers on the grinding pan 80 is almost entirely obviated. The construction of the means for regulating the fineness of the material discharged from the revolving pan has advantages in that the adjustment may be readily and quickly made, as well as 85 providing a means for readily replacing the wearing edge of such means so that the excessive wear necessarily incidental to the passage of the ground material thereunder will not necessitate the replacement of the entire 90 body of the material discharge regulating means. It will further be noted that the construction of the scrapers by means of which the material to be ground is fed to the respective mullers are adaptable to ready and easy 95 adjustment so that when the pan is revolving in the direction of the arrow on Fig. 1 the left-hand muller, as shown in this figure, will not receive more than its share of the material to be ground, thereby preventing the 100 possibility of a choking of this muller due to the entire stream of the raw material passing thereunder. By equalizing the stream passing under the respective mullers not only is the quality of the ground material 105 materially enhanced, but the power consumption of the grinder as a whole is decreased. The structure of the grinder comprising my invention is likewise particularly advantageous from the standpoint of entirely doing 110 away with right and left-hand parts, which are a constant source of annoyance and inconvenience, not only in the erection of such grinders, but in the replacement of broken or worn parts. On the whole, a grinder constructed according to the principles of my invention is much lighter than a construction in accordance with the common types now employed and a machine which is superior from 115 the standpoint of rigidity as well as longevity 120 of the various operable parts is attained.

Other modes of applying the principle of my invention may be employed instead of the one explained, changes being made as regards the mechanism herein disclosed, provided the means stated by any of the following claims 125 or the equivalent of such stated means be employed.

I therefore particularly point out and distinctly claim as my invention:

1. In a grinding mill, the combination of a supporting frame including plural supplementary elements adapted to form a hollow bell-shaped body having spaced supporting legs; a cover for said elements; a revoluble pan; reducing agencies cooperating with said pan; a vertically disposed shaft for supporting and driving said pan, and means associated with said cover for axially and laterally supporting said shaft.
2. In a grinding mill, the combination of a supporting frame including plural supplementary elements adapted to form a hollow bell-shaped body having an axially disposed hollow member; a cover for said body; a revoluble pan; reducing agencies carried by said pan; a vertically disposed shaft for supporting and driving said pan positioned within said hollow member; and means associated with said cover for axially and laterally supporting said shaft.
3. In a grinding mill, the combination of a supporting frame including plural supplementary elements adapted to form a bell-shaped body having an axially disposed hollow member; a cover for said body; a revoluble pan; reducing agencies carried by said pan; a vertically disposed shaft for supporting and driving said pan positioned within said hollow member; means associated with said hollow member for laterally supporting said shaft; and means associated with said cover for axially and laterally supporting said shaft.
4. In a grinding mill, the combination of a supporting frame including plural supplementary elements adapted to form a bell-shaped body having an axially disposed hollow member; a cover for said body; a revoluble pan; a vertically disposed shaft for supporting and driving said pan positioned within said hollow member; means associated with said cover for axially and laterally supporting said shaft; a gear wheel mounted on said shaft and enclosed by said cover; a lubricant trough in said cover positioned coaxially with said shaft; and means associated with said gear wheel for raising lubricant from said trough to the wearing surfaces thereof upon the rotation of said gear.
5. In a grinding mill, the combination of plural complementary frame members which when assembled form a hollow bell-shaped frame, a rotatable table, a hollow frame positioned coaxially within said bell, a shaft for rotatably supporting said table, means associated with said hollow frame and said bell for supporting and driving said shaft, and millers supported by said hollow frame and said bell over said table.

Signed by me, this 20th day of December, 1929.
